UNITED STATES PATENT OFFICE.

ARTHUR MAYER-SCHLIEWEN, OF NEW YORK, N. Y.

ARTIFICIAL FLOWER.

SPECIFICATION forming part of Letters Patent No. 514,482, dated February 13, 1894.

Application filed November 3, 1893. Serial No. 490,372. (No specimens.)

To all whom it may concern:

Be it known that I, ARTHUR MAYER-SCHLIEWEN, of New York city, New York, have invented an Improved Artificial Flower, of 5 which the following is a specification.

This invention relates to an artificial flower provided with a concealed tape that may be drawn out to display any picture, motto or other inscription contained thereon.

10 In the accompanying drawings, Figure 1 is a perspective view of my artificial flower, with the tape unrolled. Fig. 2 is a top view thereof and Fig. 3 a section on line x, x , Fig. 2, with the tape concealed.

15 The letter a represents an artificial flower of any suitable configuration. Centrally within the leaves of the flower, there is contained a concealed reel or drum b , hung in a frame b' , attached in suitable manner. The 20 reel may be revolved by means of an outwardly projecting handle b^2 . To the reel there is fastened one end of a tape, ribbon or band c , the free end of which carries the core or the central leaves a' , of the flower. Upon 25 the tape c , any suitable inscription or design is represented. When the tape is wound upon the reel, by means of the handle b^2 , it will be entirely concealed, while the core a' , will occupy its proper place within the outer

leaves, to produce a flower perfect in every 30 respect (Fig. 3). To expose the tape and the inscription thereon contained, it is only necessary to grasp the core a' , and draw it outward, when the tape will be unwound from the reel.

35 My artificial flower will be found to produce many delightful surprises and numerous uses for the same, as for table service, presents, &c., will readily suggest themselves.

40 What I claim is—

1. An artificial flower provided with a concealed coiled tape, adapted to be drawn out of the flower, substantially as specified.

2. An artificial flower provided with a concealed coiled tape and a core secured to the 45 free end of the tape, substantially as specified.

3. An artificial flower provided with an in- 50 closed reel, a tape secured thereto and a core secured to the tape, substantially as specified.

4. An artificial flower provided with an in- 55 closed reel having an outwardly projecting handle and a tape secured to the reel, substantially as specified.

ARTIIUR MAYER-SCHLIEWEN.
